(57) **CLAIM**

The ornamental design for a pot valve, as shown and described.

DESCRIPTION

FIG. 1 is a perspective view of a pot valve showing my new design;

FIG. 2 is a front view thereof;

FIG. 3 is a rear view thereof;

FIG. 4 is a left side view thereof;

FIG. 5 is a right side view thereof;

FIG. 6 is top view thereof;

FIG. 7 is a bottom view thereof; and

FIG. 8 is another perspective view thereof; and,

FIG. 9 is an operational right side view of the pot valve mounted under a teapot.

The broken lines are shown for illustrative purposes only and form no part of the claimed design.
